UNITED STATES PATENT OFFICE.

THOMAS B. BLAKE, OF DEMOPOLIS, ALABAMA, ASSIGNOR OF ONE-HALF TO J. R. VANCE, OF DEMOPOLIS, ALABAMA.

FOOT-MEASURE.

1,391,714.

Specification of Letters Patent. Patented Sept. 27, 1921.

Application filed May 28, 1918. Serial No. 237,038.

To all whom it may concern:

Be it known that I, THOMAS B. BLAKE, a citizen of the United States, and a resident of Demopolis, Marengo county, Alabama, have invented new and useful Improvements in Foot-Measures, of which the following is a specification.

This invention relates to foot measuring appliances adapted for use by shoe salesmen to determine the proper size shoe for the customer.

The principal object of the invention is to provide a device of this character which will indicate at a single operation both the length and the width of the shoe required, and which also may be used without change of any of its parts for either the right or left foot.

A further object of the invention is to provide a device of this character which is of simple construction, low manufacturing cost and of such simple operation as to give accurate results even in the hands of a novice.

25 A further object of the invention is to provide a device of this character which embodies but a single adjustable gage member for indicating both the length and the width, and in which the gage member is so designed as to be capable of an accurate micrometer adjustment through a rotative part through which the degree of pressure applied to the foot may be determined. Means are also provided to retain the gage member in its adjusted position unless the pressure against the foot is excessive.

30 A further object of the invention is to provide a device of this character which may be readily combined with the ordinary shoe salesman's seat as an adjunct to the foot rest against which the shoes are fitted, and without interference with the use of the foot rest for that purpose.

In the accompanying drawings I have 45 illustrated a preferred embodiment of my invention as a detached article and also in a form to be used in conjunction with a foot rest.

In said drawings, 50 Figure 1 is a plan view of the foot measuring device for separate use;

Fig. 2 is a longitudinal section on line 2-2 of Fig. 1;

Fig. 3 is a transverse section on line 3-3 55 of Fig. 1;

Fig. 4 is a side elevation partly in section of an ordinary shoe salesman's seat showing my foot measuring device in position thereon;

Fig. 5 is a longitudinal sectional view 60 similar to the corresponding portion of Fig. 4 and showing the foot measuring device adjusted to permit the usual use of a foot rest for fitting the shoes;

Fig. 6 is a plan view of the foot rest portion of the seat shown in Fig. 4 with the measuring device positioned for measuring the right foot; and

Fig. 7 is a similar view with the device positioned for measuring the left foot. 70

Referring to the drawings, particularly to Fig. 1, 1 indicates the base of the device, here shown as a board having a raised flange 2 around three of its edges. Attached to the face of the board adjacent the remaining 75 edge is a pair of parallel tracks 3 spaced somewhat above the face of the base by the supporting brackets 4 at each end.

Mounted to slide on the rods 3 is a carriage 5 comprising a lower sheet metal portion having each end bent around the rods as indicated at 6 in Fig. 3, and an upper sheet metal portion 7 having edge flanges at right angles to the rods to form a guideway for the gage member 8 to permit the 85 transverse adjustment of the gage member toward and away from the rods and toward and away from the long edge flange of the base board. The under side of the upper 90 part 7 fits flat on the lower part and the two parts of the carriage are rigidly connected by brazing or rivets or in any suitable manner, or the two parts may be made in one integral piece.

The gage member comprises a stem 9 95 working in a guideway formed by the upper piece 7 of the carriage, the edges of the side flanges of the guide being bent over the edges of the stem to retain the gage member in position. The stem of the gage member 100 is slotted as indicated at 10 to receive a gear 11 formed on the lower end of a knurled knob 12, the gear teeth projecting into the slot and meshing with rack teeth 13 formed along one edge of the slot. The knob 12 is 105 mounted for rotation on a fixed pin or spindle 14 set in the center of the carriage 5 and is formed with a flange above the gear teeth as indicated at 15, which rests on the upper face of the stem 9 on each side of the 110

slot and is held pressed against the stem by a spiral spring 16 retained in a recess in the knob beneath the head of the pin 14.

The inner end of the gage piece is bent 5 down to rest upon the face of the board, as shown in Fig. 3, and consists of an elongated flat bar 17 integral with the stem and at right angles to it, and with its ends turned away from the stem toward the long 10 flange of the base board and pointed to act as indicators in conjunction with the scale marks 18 stamped on the face of the board. In the middle of the bar 17 opposite the stem 9 there is provided a vertical slightly 15 concave foot engaging member 19 which in the use of the device is adjusted against the ball of the foot as indicated more particularly in Fig. 1.

The scale 18 is a double scale, one for 20 the left foot and one for the right, and one coöperating with one point of the bar 17 and one with the other. Each scale comprises a series of spaced lines extending 25 in a general longitudinal direction but at an angle to the long edge of the base board, the lines being most distant from the flange at the long edge of the base board at the ends of the board and inclining in the direction of the flange from the end to the middle, 30 where they join the corresponding lines of the other scale.

These lines indicate the width of the shoe required and are marked with appropriate width designations such as A, B, C, D, 35 etc. The scales also comprise lines for indicating the length of the shoe required, these lines being parallel with the ends of the board and being spaced apart the proper distance to indicate the different shoe 40 sizes. The lines indicating the smallest sizes are at the center. As shown in the drawing, the sizes are shown by the ordinary numbers 3, 4, 5, etc., but of course, arbitrary designations may be used for indicating 45 the lines for both the width and the length.

In using the gage the board is placed upon the floor and the customer stands with the foot to be fitted in the corner of the 50 board with the outside of the foot pressed against the long side flange of the base board and the heel against the end flange in the position indicated in dotted lines in Fig. 1. The carriage 5 is then adjusted along the 55 rods to a position opposite the ball of the foot and the knob 12 is then turned to adjust the gage piece 17 inward until the curved foot engaging piece 19 fits against the side of the joint in the manner indicated.

60 The pointed end of the gage piece 17 in advance of the toe will then overlie one of the squares formed by the intersecting scale lines and the most nearly adjacent scale lines would indicate the proper size and 65 width of the shoe.

The gear and rack connection between the knob and the gage piece permit a nice regulation to be secured in the pressure of the gage piece against the foot, so that the piece may be adjusted to indicate the proper 70 width for a snug or loose fit as desired by the customer. After a little practice the shoe salesman can easily tell by the resistance to rotation of the knob, the degree of pressure he is applying to the foot. The 75 spring 16 between the knob presses the flange piece at the base of the knob against the stem of the gage piece with sufficient friction to hold the gage piece in its adjusted position unless the pressure against 80 the foot is considerably greater than desirable in any case.

The knob 12 not only serves to adjust the piece 17 toward and away from the foot by its rotative movement, but also serves 85 as a convenient means for shifting the carriage 5 longitudinally of the rods so that any adjustment for measuring both the length and width may be made by taking hold of the knob and adjusting it with 90 relation to the foot in the manner experience indicates to be proper.

In measuring the other foot the board will be turned around so that the customer has to stand with the foot in the opposite corner 95 of the board, that is, the upper left hand corner of the board, as shown in Fig. 1, in which position the point at the right end of the piece 17 will indicate the proper size shoe.

I preferably also print on the face of the board a short scale 20, along the long side flange of the board for the purpose of indicating the proper length of children's shoes, which are shorter than half the length of 105 the board. This scale is not used in conjunction with the gage. When the child stands with his foot in the corner of the board the salesman can see at a glance which size shoe will be sufficiently longer 110 than the foot for correct fitting.

In Figs. 4, 5, 6 and 7 I have indicated my improved foot measuring device as designed to be used in conjunction with the ordinary salesman's seat. As here shown, 115 25 indicates the ordinary shoe salesman's bench having the horizontal seat 26 for the salesman and an end portion 27 inclined downward as indicated, upon which the customer places his foot for fitting. These 120 benches are of ordinary construction, with the part 27 of a solid board covered with a rubber mat against which the customer may press his foot without marring the shoe. To utilize my foot measuring device 125 the part 27 consists of an open box into which the base board 28 of the foot measuring device is fitted after the manner of a box lid, the under face of the base board being cut out around its edges to fit in the 130

box and be supported on the shallow side flanges 29.

The foot measuring device will preferably be of the same construction as above described, except that the base board may be provided with flanges on the fourth side also, as indicated at 30 in Figs. 6 and 7, the flanges 30 being cut adjacent the end of the shank 9 on the gage piece as indicated at 31 so as to permit the full amplitude of adjustment of the gage piece.

The four side flanges of the base board are positioned to fit within the box when the board is inverted, as indicated in Fig. 5, so that the under face of the board will be employed for the usual purpose of fitting the shoes, to which end its surface will preferably be covered with a rubber pad as indicated at 32, the box 27 being deep enough to receive the projecting parts of the foot measuring device and allow the base board to fit snugly in the box with its extension edge resting against the edges of the sides of the box.

In operation the base board will be first set in position with the foot measuring device on the upper side, and with the continuous side flange at the right or the left, according to the foot it is desired to measure. After the proper size is determined for that foot, for instance the right foot, as shown in Fig. 6, the board is turned around as shown in Fig. 7, and the other foot measured, after which the base board is inverted and replaced in the box to allow the rubber surface 32 to be used in fitting the shoes.

The specification and drawings disclose a preferred embodiment of the invention as it has been found most useful in actual practice, but it is to be understood, however, that the details of construction disclosed may be varied in many particulars without departing from the spirit of the invention or the scope of the appended claims.

45 Claims:

1. In a foot measure, the combination of a base board or plate, separate scales marked thereon for the right foot and the left foot comprising indications for length and width, means for locating the foot to be measured with relation to its scale and a single indicating member adjustable with relation to the foot to be measured adapted to coöperate with both scales and to indicate the size and width of the foot being measured.

2. In a foot measure, the combination of a base board or plate having a scale marked thereon having indications for length and width and also for the right foot and the left foot, separate abutments for the left foot and the right foot, respectively, and a single indicating member adjustable with relation to the foot to be measured when said foot is placed against its abutment and adapted to indicate on said scale the length and width of shoe for either foot.

3. In a foot measure, the combination of a base board, or plate, abutments thereon for the left and right foot, respectively, at the opposite ends of said board, said board having scales for the separate feet and a single indicating member having two points, one for each scale, means for adjusting said indicating member toward and from said abutments, and means for yieldingly holding said indicating member in its adjusted position.

4. In a foot measure, the combination of a board having abutments at each end and at one side, said board having scale lines parallel with the end abutments for indicating the shoe lengths for the left foot and for the right foot, respectively, when the foot is placed against one of the end abutments, other scale lines extending diagonally from the end abutments toward the middle and inclined toward the side abutment for indicating the width of shoe, and means carried by said board and adjustable with regard to said abutments for designating the scale marks for the foot being measured.

5. In a foot measure the combination of a board having abutments at each end and at one side, said board having scale lines parallel with the end abutments for indicating the shoe lengths for the left foot and for the right foot, respectively, when the foot is placed against one of the end abutments, and other scale lines extending diagonally from the end abutments toward the middle and inclined toward the side abutment for indicating the width of shoe, an indicating member carried by said board adjustable both longitudinally and transversely thereof for indicating the proper scale marks for the foot being measured.

Signed at Demopolis, in the county of Marengo and State of Ala., this 1st day of May, 1918.

THOS. B. BLAKE.
